B. S. Nichols, of Seneca Falls N.Y.

Assignor to

Downs & Co. Manufacturing Company of same place

Letters Patent No. 2293. Dated April 3, 1866.

Design for a Pump.

The schedule referred to in these Letters Patent, and making part of the same

To all whom it may concern

Be it known that I, B. S. Nichols, of Seneca Falls, in the County of Seneca, and State of New York, have invented or produced a new and original Design for Pumps; and I do hereby declare that the following is a full and exact description thereof, reference being had to the accompanying drawing, making part of this specification.

The figure represents a perspective view of the Pump.

This pump belongs to that class known as "cistern or well pumps." The object is to give the pump a symmetrical and ornamental contour and form, to adapt it to this peculiar construction.

The pump consists essentially of a base A, a cylinder or body B, and a revolving, closed top C, changeable to different positions and having connected therewith, the usual handle D, for operating the parts.

The base consists of a rim or flange a, for securing to the platform, having above it a corrugated or ribbed pedestal b, to which the cylinder B, is attached by means of screws c, and flanges d, e, on opposite sides. By means of this attachment, the interior works are reached.

The bottom of the cylinder resting on the base, is formed

with a graceful swell or enlargement *g*, as shown, having at its top a rim or rib *h*. Above this is situated the cylinder proper *i*, in which the piston works, having simply two rings *k*, *k*, cast upon its periphery. Next is a rim *l*, similar to *h*; and above this a vertically corrugated or ribbed section *m*, surmounted by the reservoir or chamber *n*, with which connects the spout *o*.

This chamber is made of considerably larger diameter than the cylinder proper. It is made simply plain or smooth upon the outside, and is either globular or somewhat elongated. Above the chamber is another rim *p*, and a corrugated or ribbed section *q*, similar to *m*; and still above this a rim *r*, and finally the closed revolving top *c*. The spout is also provided with rims *u*, *v*, and a projection *w*.

The design above described gives a symmetrical and graceful outline to the pump, which owing to its considerable height, to enable the bucket or pail to be placed under the spout, would otherwise appear slender and disproportionate. The chamber or bulb *n*, by being of considerable size, relieves this disproportion by breaking the monotony; while on the other hand, the plainness and smoothness of the bulb and cylinder are relieved by the corrugated or ribbed parts *b*, *m*, *q*, and the rims and rings *h*, *l*, *p*, *k*. To give still further effect to the design, the parts *c*, *h*, *l*, *p*, *t*, *u*, *v*, *w*, are tipped with bronze after the pump is painted.

What I claim is the design for a pump as herein shown and set forth.

Witness,

Chas. A. Hawley

S. S. Gould
